UNITED STATES PATENT OFFICE.

PEARL J. WENTWORTH, OF BOSTON, MASSACHUSETTS, ASSIGNOR TO UNITED SHOE MACHINERY COMPANY, OF PATERSON, NEW JERSEY, A CORPORATION OF NEW JERSEY.

SHOE-SHAPING MACHINE.

1,157,741.

Specification of Letters Patent. Patented Oct. 26, 1915.

Application filed January 9, 1914. Serial No. 811,203.

To all whom it may concern:

Be it known that I, PEARL J. WENTWORTH, a citizen of the United States, residing at Boston, in the county of Suffolk 5 and State of Massachusetts, have invented certain Improvements in Shoe-Shaping Machines, of which the following description, in connection with the accompanying drawings, is a specification, like reference characters on the drawings indicating like parts in the several figures.

This invention relates to the manufacture of boots and shoes and particularly to machines for use in the shaping of turn shoes 15 to conform the shoe accurately to the shape of the last and to give it a smooth and finished appearance.

An object of the invention is to effect improvements in the construction of machines of this general class, and to this end a feature of the invention resides in means which may be suitably positioned to treat a shoe presented thereto at one side of the machine, with provision for bodily movement 25 of the shoe treating means laterally at the convenience of the operator from its location for use to an idle position upon the machine. One form of such means may comprise, as shown, a tool arranged to beat 30 the work by rapid impulses, together with an operating device, such as a suitably rotated cam, for imparting to the tool its shoe beating movements and into and out of operative relation to which the tool is 35 mounted to swing.

A further feature of the invention consists in the combination of shoe beating means and shoe ironing means movable alternatively into operative position for treating a shoe presented at one side of the machine. As herein shown the machine includes upper beating and ironing tools that are in some respects similar in construction and relative arrangement to those disclosed 40 in United States Letters Patent No. 876,249, granted to S. J. Wentworth, Jan. 7, 1908, with provision for lateral movement of the spindle which carries the beating tool and is encircled by the ironing tool, so as to 45 bring either of said tools into suitable relation to the operator as he stands in front of the machine. With this arrangement it is not necessary for the operator to change his position materially in presenting the

shoe to the different tools, and the machine 55 embodies means to enable him to bring the different tools to position quickly without material effort or waste of time.

A further feature of the invention resides in the combination of a beating tool and an 60 ironing tool movable alternatively into position to treat a shoe and means for maintaining said tools in heated condition. Either tool is thus maintained in readiness for instant use whenever required. In the 65 preferred arrangement, which includes a reciprocatory spindle that is encircled by the ironing tool, the heater comprises an electrical heating unit located at that portion of the spindle which is within the 70 ironing tool.

These and other features of the invention, including certain details of construction and combinations of parts, will now be described with reference to the accompanying 75 drawings and pointed out in the claims.

In the drawings, Figure 1 is a side elevation of a machine embodying the preferred form of the invention, Fig. 2 is an enlarged perspective view of the upper portion of the 80 machine, with certain portions broken away for clearness, Fig. 3 is a vertical section through the machine head and the shoe treating tools, Fig. 4 is a fragmentary plan view illustrating the operation of the beat- 85 ing tool upon a shoe.

Upon the frame 2 of the machine is formed a boss 4 which provides a bearing for a vertical spindle 6. Secured to the spindle at its upper end by means of a pin 90 8 is a tool carrying head 10 which is thus rotatable with the spindle and rests upon the upper end of the boss 4. The head is bored horizontally to receive a reciprocating rod or spindle 12 which carries at its 95 outer end a beating tool 14. A key 16 enters a flat keyway 18 in the rod 12 and serves to prevent rotation of the rod and to limit the reciprocating movement of the rod in both directions. The rod 12 is held 100 normally at its forward limit of movement by a spring 20, and in operation is moved backwardly by the pressure of a shoe against the beating tool 14, with the upper presented to the tool in the relation shown in 105 Fig. 4, until the rear end of the rod projects into the path of a rotary cam 22 which will thus impart to the rod and beater a rapid

succession of forward shoe beating movements as long as the shoe is pressed against the beater. The cam 22 is carried by a belt driven shaft mounted in a bearing carried 5 by a standard 23 on the frame.

Secured to one side of the head 10 is a bar 24 which is bored to receive one end of a rod 26 and has a spring 28 in the bore to force the rod outwardly. The rod 26 is 10 provided with a bracket 30 which carries a roller 32. The arrangement is such that this roller is below the beater and projects somewhat forwardly therefrom. Rotation of the rod 26 is prevented by a rod 34 carried 15 by the bracket 30 and projecting through a bore in a lug on the bar 24. In the beating operation the shoe is placed in contact with the roller 32, which may be forced backward in opposition to the force 20 of the spring 28 together with the beater, and the roller serves as a guide for positioning the shoe, especially during the beating of the end portions thereof.

The beating device thus far described except as to the rotation of the supporting head, is similar in construction and mode of operation to that disclosed in United States Letters Patent No. 844,293, granted to S. J. Wentworth, Feb. 12, 1907.

30 Encircling the spindle 12, somewhat in the manner disclosed in United States Patent No. 876,249, previously referred to, is an ironing tool 36 which is mounted rotatably on a bearing 38 on the head and has a flange 35 40 which is held against the end of this bearing by one end of the spring 20. In the ironing operation the shoe is moved in rolling contact with the periphery of the tool 36 which is rotated on its bearing 40 through contact with the shoe.

It will be readily seen that for the beating operation the spindle 12 should project forwardly toward the operator, while for the ironing operation the tool 36 should project 45 laterally in front of the operator to bring its peripheral surface into proper position to receive the shoe. To effect such change of position of the tools the arrangement provides for rotation of the head 10 back 50 and forth through substantially ninety degrees. The spindle 6 projects downwardly through a bearing 42 formed in a bracket 44 on the frame and has at its lower end a crank arm 46 with a pin 48 that engages in a slot 50 formed in a lever 52 which is pivoted at 54 to the bracket 44. At its forward 55 end the lever carries a member 56 to be engaged by the operator's leg for swinging the lever. With the parts arranged as 60 shown it will be clear that a comparatively small movement of the lever will serve to rotate the head 10 sufficiently to bring the tools into the position represented by dotted lines for the ironing operation, and 65 that by a reverse movement of the lever the

parts may be returned to their first position to beat a shoe. For retaining the head 10 in either position of adjustment the boss 4 is provided with two depressions 58 substantially ninety degrees apart, and the head 10 70 has a projection 60 which is bored to receive a spring held plunger 62 the end of which is rounded to enter said depressions so as to oppose but not prevent rotation of the head. As an additional safeguard to prevent rotation of the head when the shoe is 75 pressed against the ironing tool, the boss 4 is provided with a projection 64 with which the projection 60 on the head engages when the parts are in the dotted 80 line position. This arrangement effectively prevents further swinging movement of the ironing tool away from the operator.

It is necessary to provide heating means for the ironing tool, and for the best results also it is desirable that the tool 14 be heated to some degree. The machine includes an arrangement whereby both tools may be heated effectively from the same heating device. As shown in Fig. 3, an electrical heating element 66, supplied with current by wires 68, is located within the spindle 12 at such a point as to be encircled by the tool 36. The heater will thus serve to heat the ironing tool to the required degree, and at the same time is sufficiently close to the tool 14 to impart to this tool also a substantial degree of heat. The wires 68 extend, as shown, through a bore in the spindle 12 and out at one side of the spindle and through a notch 70 in the head 2 so as not to interfere with the reciprocation of the spindle in beating a shoe. With this arrangement both tools are maintained in heated condition ready for instant use. 100

In using the machine, the workman stands in front thereof with one leg in engagement with the member 56. With the parts in the position shown in the drawings the spindle 12 is in operative relation to the cam 22 so as to be engaged by the cam when the spindle is moved endwise by pressure of a shoe against the tool 14. The cam will thus impart a rapid succession of shoe beating movements to the tool. When it is desired to iron the upper the operator swings the lever 52 a short distance and thereby turns the head 10 so that the tools assume the position represented by dotted lines, the plunger 62 slipping out of the forward depression 58 and into the rearward depression and the projection 64 effectively preventing further rotation of the head in this direction. The ironing tool is now in position to treat the shoe in the well known manner. When it is desired to resume the beating operation the parts may be returned instantly to their first position by a reverse movement of the lever 52. 110

Although the machine has been described 130

as especially intended for operating upon turn shoes, it will be obvious that it may be used to treat any shoe that may be subjected advantageously to upper beating and ironing operations. It will be understood also that although the invention has been disclosed as embodied in a machine having the specific features of construction shown and described, the invention is not thus limited in its application, and that other embodiments are comprehended within the spirit and scope thereof as defined by the claims.

Having described the invention, what I claim as new and desire to secure by Letters Patent of the United States is the following:

1. A machine of the class described having, in combination, shoe beating means and shoe ironing means movable alternatively into position to operate upon a shoe presented thereto at one side of the machine, and means whereby either of said means may be moved into said operative position.

2. A machine of the class described having, in combination, shoe beating means arranged to operate upon a shoe presented at one side of the machine and movable out of said operative position, and ironing means for operating upon a shoe presented thereto at the same side of the machine and movable into said operative position through said movement of the beating means out of operative position.

3. A machine of the class described having, in combination a tool carrying head, and a beating tool and an ironing tool both carried by the head, said head being movable to bring either of said tools into position to operate upon a shoe presented thereto at one side of the machine.

4. A machine of the class described having, in combination, a beating tool, a spindle carrying said tool, and an ironing tool arranged about said spindle, said spindle being movable to bring said tools alternatively into position to operate upon a shoe presented thereto at one side of the machine.

5. A machine of the class described having, in combination, a rotatable tool carrying head, a beating tool and an ironing tool both carried by said head, and means whereby the head may be rotated to bring said tools alternatively into position to operate upon a shoe presented thereto at one side of the machine.

6. A machine of the class described having, in combination, a tool carrying head, a spindle projecting laterally from the head and having a beating tool at the outer end thereof, and an ironing tool carried by the head and encircling the spindle, said head being rotatable through substantially ninety degrees to bring said tools alternatively into position to operate upon a shoe presented thereto at one side of the machine.

7. A machine for use in the manufacture of shoes having, in combination, a spindle, a rotatable tool encircling the spindle, a reciprocable tool carried by the spindle and movable in the direction of the length of the spindle, a mounting for the spindle permitting its adjustment into position for either tool to face the operator, and operating means into operative relation to which the reciprocating tool is moved when it is positioned to face the operator and out of operative relation to which it is moved when the rotatable tool is positioned to face the operator.

8. A machine for use in the manufacture of shoes having, in combination, a spindle, a rotatable tool encircling the spindle, a reciprocable tool carried by the spindle and movable in the direction of the length of the spindle, and a mounting for the spindle permitting its adjustment into position for either tool to face the operator.

9. A machine for use in the manufacture of shoes having, in combination, a tool arranged to beat the work by rapid percussional impulses, and an actuator into and out of operative relation to which the tool is mounted to swing laterally.

10. A machine for use in the manufacture of shoes having, in combination, a tool arranged to beat the work by rapid percussional impulses, an actuator, and mountings permitting the tool to be pressed by the work into position to be moved by the actuator, said mountings being constructed and arranged to permit the tool to be swung laterally away from its operative relation to the actuator.

11. A machine for use in the manufacture of shoes having, in combination, a shaft, a cam on the shaft, a beater, and mountings by which the beater may be positioned to extend at right angles to the shaft in operative relation to the cam and permitting the beater to be positioned parallel with the shaft out of operative relation to the cam.

12. A machine for use in the manufacture of shoes having, in combination, a supporting frame, an ironing roll, a supporting spindle for the roll, and connections from the spindle to the frame permitting the spindle to be turned about a vertical axis to locate the roll in positions substantially 90° apart.

13. A machine of the class described having, in combination, a rotatable tool carrying head, a beating tool projecting from the head in position to operate upon a shoe presented thereto at one side of the machine in one position of the head, yielding means for retaining the head in said position, an ironing tool carried by the head and arranged to operate upon a shoe presented thereto at the same side of the machine when the head is rotated to a different position, and means

for rendering the head rigid to resist pressure of the work against the ironing tool in the latter position.

14. A machine of the class described having, in combination, a rotatable tool carrying head, a beating tool and an ironing tool both carried by the head, and means whereby said head may be rotated to bring either of said tools into position to receive a shoe comprising a spindle carried by the head and projecting downwardly therefrom, a crank on the spindle, and manually operative means for engaging said crank to effect rotation of the head.
15. A machine of the class described having, in combination, a reciprocatory tool carrying spindle, a beating tool carried by the spindle, an ironing tool encircling the spindle, the spindle being movable to pre-

sent either of said tools alternatively in position to treat a shoe, and heating means for both said tools located at that portion of the spindle which is encircled by said ironing tool.

16. A machine of the class described having, in combination, a beating tool and an ironing tool constructed and arranged for movement to present either tool alternatively in position to treat a shoe, and means for maintaining both said tools in heated condition.

In testimony whereof I have signed my name to this specification in the presence of two subscribing witnesses.
